WITNESS

UNITED STATES PATENT OFFICE

JAMES F. KELLY, OF CLIFTON, NEW JERSEY

WALL CONSTRUCTION

Application filed January 24, 1930. Serial No. 423,217.

This invention relates to wall construction of the veneer type, wherein a brick or tile veneer is secured upon the outer face of a wood or frame building to give the walls of the building the appearance of solid brick or tile walls.

An object of the present invention is to provide novel means for attaching the brick or tile to the wooden structure, the means employed being simple, inexpensive and easily applied, so that the cost of both material and labor will be reduced to a minimum.

With the above and other objects in view, the invention further includes the following novel features and details of construction, to be hereinafter more fully described, illustrated in the accompanying drawings and pointed out in the appended claims.

In the drawings:—

20 Figure 1 is an elevation showing a fragmentary portion of a wall with the invention applied.

Figure 2 is an enlarged fragmentary vertical sectional view.

25 Figure 3 is a perspective view of one of the brick or tile.

Figure 4 is a like view showing a portion of one of the attaching strips.

Figure 5 is a fragmentary section showing 30 the invention applied to a flat wall.

Referring to the drawings in detail where-in like characters of reference denote corresponding parts, the reference character 10 indicates a brick or tile which may be made of any suitable material such as clay, cement or asbestos, and may be of any suitable dimensions or shape. The brick or tile shown are rectangular and are provided upon their inner faces with longitudinally disposed 35 grooves 11 whose upper walls are inclined as shown at 12, the inclination being such that the inner or bottom walls of the grooves are of greater width than the width of the entrances.

40 Extending from the grooves 11 are notches or recesses 13. These notches or recesses extend from the upper inclined walls 12 and may be positioned at any point throughout the length of the grooves.

45 The reference character 14 indicates me-

tallic strips which may be either solid or hollow. These strips are provided with upper inclined faces 15 and when these strips are secured to a wall, these faces incline rearwardly and downwardly as shown in Figure 55 2 of the drawings. Rising from the inclined faces 15 of the strips are spaced projections 16 which are adapted to be received within the notches or recesses 13.

The strips 14 are secured to the wall 60 through the medium of nails or fastening devices 17 which pass through openings 18 provided in the strips. The strips are disposed horizontally of the walls and in vertically spaced relation, with the projections 16 of 65 adjacent strips staggered. The brick or tile 10 are then placed upon the strips with the inclined walls 12 engaging behind the inclined faces 15 of the strips and the projections disposed within the recesses or notches 70 13. The slots 11 being of greater width than the strips 14, the brick or tile 10 may be readily placed upon the strips. The brick or tile will thus be held against longitudinal sliding movement as well as outward movement 75 and will be so positioned as to break joints after the manner of the usual brick wall. The spaces between the adjacent edges of the brick or tile are provided with a plastic filling 19 of cement or other suitable material 80 to represent mortar courses.

In Figure 2, the brick or tile have their rear faces 20 inclined and are adapted to be used upon the outside of a clap-board wall 21, while the brick or tile 10a shown in Figure 85 5 of the drawings have their inner and outer faces parallel and are adapted to be applied to flat vertical walls 22.

The invention is susceptible of various changes in its form, proportions and minor 90 details of construction and the right is herein reserved to make such changes as properly fall within the scope of the appended claims.

Having described the invention what is 95 claimed is:—

1. In a wall construction, a base, vertically spaced horizontally disposed strips secured thereto, said strips having inwardly inclined upper faces, bricks having longitudinally disposed slots in their rear faces to receive 100

the strips, said slots having inclined upper walls for engagement over the inclined faces of the strips to provide an interlocking engagement, means to hold the bricks against independent longitudinal movement on said strips, and a plastic filling between the adjacent edges of the strips.

2. In a wall construction, a base, vertically spaced horizontally disposed strips secured thereto, said strips having inwardly inclined upper faces, projections extending vertically from the inclined faces of the strips, bricks having longitudinally disposed slots in their rear faces to receive the strips, said slots having inclined upper walls for engagement over the inclined faces of the strips and having notches extending from said walls to receive the projections of the strips and provide an interlocking engagement, and a plastic filling between the adjacent edges of the bricks.

In testimony whereof I affix my signature.

JAMES F. KELLY.
